CALCULATING MACHINE

Howard M. Dustin, Berkeley, Calif., assignor to
 Marchant Calculating Machine Company, a
 corporation of California

Application May 13, 1941, Serial No. 393,207

6 Claims. (Cl. 235—79)

This invention relates to a calculating machine of the type designed to perform four cardinal calculations.

The invention more particularly refers to that type of calculating machine in which a selective transmission is incorporated between the operating member or hand-crank and the differential actuator, whereby a single operation of the operating member may be caused to insert an entry any selected number of times in the accumulator register. In such a calculating machine it is desirable to disengage the accumulator register from the actuator of the machine at the conclusion of each cycle of operation of the operating member and to engage the accumulator register and actuator and maintain such engagement throughout a suitable actuating period.

It is a general object of the present invention to provide an improved and simplified mechanism for effecting engagement and disengagement between the accumulator register and the actuator.

It is a further object of the present invention to provide a mechanism capable of maintaining the accumulator register in engagement with the actuator during a plurality of cycles of operations, which mechanism is operable independently of the numbers of cycles through which a machine is operated.

It is a further object of the present invention to provide an improved and simplified mechanism for maintaining a desired setting of the selection mechanism during a plural cycle operation.

It is a further object of the present invention to set and to maintain in the set position certain members associated with a "crawl carry" type of accumulator mechanism.

Various other objects and advantages of the present invention will appear from the following description of a preferred form of machine embodying the present invention, for which purpose reference is made to the accompanying drawings, in which,

Figure 1 is a longitudinal section, as viewed from the right, showing the general arrangements of the parts of the machine.

Figure 2 is a detailed section, as viewed from the right, showing the members which constitute the centralizing and interlocking means for the selective speed transmission unit.

Figure 3 is a right side view of the mechanism for locking the selection levers in position while actuation is taking place.

Figures 4 to 7, inclusive, are detail views of parts of the selection mechanism.

Figure 8 is an enlarged view partly in section of two orders of the accumulator, showing the construction thereof.

Figure 9 is a right side view of the carriage showing parts of the accumulator planetary gear train.

Figure 10 is a developed plan view partly schematic and partly in section of the selective speed transmission unit, and its drive to the actuator and related mechanisms.

Figure 11 is a right side view of the mechanism for releasing and for locking the actuator drive gears.

Figure 12 is a right side view of the actuator centralizer and the means for locking the actuator in full cycle position.

The machine embodying the invention includes a shiftable numeral wheel carriage having an accumulator register which is engaged with the actuator mechanism during the actuating period and disengaged therefrom subsequent to the actuating period to permit shifting of the carriage. The accumulator register is of the crawl carry type in which partial digital increments are transferred from adjacent numeral wheels in the process of "carrying the tens." At the conclusion of an operation, therefore, the numeral wheels are backed up the amount of this partial increment so that they are brought into correct alignment.

In hand-operated calculating machines having mechanisms for conditioning the machine for calculation operation, such as shown in the Chase Patent No. 2,233,912, an enabling device is provided to control the conditioning mechanism in such a way that the latter is rendered effective at the beginning of the operation of the hand-crank.

The enabling device is driven in time with the actuator and is adjusted during the initial operation thereof in such a way as to maintain the conditioning mechanism effective throughout a multicyclic operation of the actuator. At the conclusion of such a multi-cyclic operation the hand crank is overdriven beyond its full cycle position and subsequently returned to its full cycle position, at which time the enabling device is readjusted to its initial position to permit return of the conditioning mechanism to disabled position so that shifting or clearing operations may subsequently be initiated. In the present machine, on the other hand, the enabling device is driven in time with the hand-crank independently of the cycles of the actuator, and enables and main-

tains the conditioning mechanism in operation throughout any number of actuator cycles which might be effected during the actuating period of the hand-crank cycle, and then effects return of the conditioning mechanism at a fixed time in the actuating period, without the necessity of any extra cyclic movement of the hand-crank.

Selecting and actuating mechanism

The numeral keys 15 (Fig. 1), by means of which the factors are entered into the machine, are arranged in parallel rows of ten keys each, one such row being shown in the drawings. Each key 15 is mounted on a key stem 16 which is vertically slidable in a key frame 9 and normally maintained in raised position by a spring 6 compressed between a lug on the key stem and the key frame.

The keys are adapted to be latched down by a lock bar 40 (Fig. 1) having a hook 92 for each key, which snaps over the top of a part of the key stem when the key is depressed as described more fully in the Avery application, Serial No. 367,025, filed November 25, 1940.

A second bar 50 has a series of notches 59 placed at intervals slightly less than the distance between the keys so that depression of the keys slides the bar towards the right different amounts. A lever 58 having a gear segment 57 meshing with a pinion 56 integral with the numeral wheel 52 is pivotally mounted on a shaft 67. This lever is connected to the bar 50 so that the differential movement thereof in response to the depression of a selected key rotates the numeral wheel 52 to the position indicative of the key depressed.

Also, underlying the numeral keys are a series of selection bars 450 (Figs. 1 and 3), 440, 430, 420, and 410 shown partly in Figs. 4 to 7, inclusive. The bar 450 (Fig. 1) is known as the 5-6 selection bar and is controlled by the five and six numeral keys to set the numeral wheel actuator, explained hereinafter, for a five or six actuation. This bar has a series of notches, notch 452 of which normally lies to the left of the five key stem so that depression of this key slides the bar towards the right from the neutral position shown. Similarly, a second notch 451 lies to the right of the six key stem and depression thereof moves the selection bar toward the left. The remaining notches 455 lie directly under the remaining keys so that depression thereof has no effect upon the bar. The other selection bars are related similarly to the other keys and effect a setting of the actuator in accordance with the keys depressed. These bars bring certain gears, explained hereinafter, into mesh and establish differential driving ratios between three actuator shafts 166, 167, and 168 (Fig. 1) and the product numeral wheels so that one cycle of the actuator shafts may drive the numeral wheels through 1 to 9 digital increments.

The actuator shafts 166, 167, 168 (Figs. 3 to 7 and 10), hereinafter referred to as the half, quarter, and twelfth speed shafts, respectively, are common to all denominational orders of the machine and are connected to the driving mechanism through suitable gearing and transmission devices, shown in Fig. 10, so that shaft 166 rotates through 180°, shaft 167 through 90°, and shaft 168 rotates through 30° for each cycle of operation of the machine.

A gear 189 and an integral sleeve 179 (Figs. 1 and 7) are mounted on a shaft 170 in each denominational order and are adapted to be con-

nected to the actuator gear train and driven by one of the three shafts 166, 167, or 168 at any one of nine different rates with respect to the driving means, said rates corresponding to the values delineated on the keys 15. Since this mechanism is repeated in each denominational order of the machine only one such order will be described in detail.

Five and six selection adjustment

As shown in Figure 3, a gear 471 is keyed to the sleeve 179 and there is mounted to oscillate freely on a spacer mounted on said sleeve adjacent gear 471, a selection plate 472 having rotatably mounted thereon an idler gear 473 and an idler gear 474 entrained with gear 471. Keyed to the half speed shaft 166 and in alignment with gear 473 is a twelve-tooth gear 475, while in alignment with gear 473 on the opposite side is a twenty-tooth gear 476 keyed to the quarter speed shaft 167. Thus, if plate 472 is swung to the right, upon depression of the "5" key (Fig. 1) gear 473 (Fig. 3) will be brought into mesh with gear 476, whereupon the 90° rotation of shaft 167 during each cycle of operation of the machine will advance the gear 471 five teeth; while if plate 472 is swung to the left, upon depression of the "6" key gear 473 will be carried into mesh with gear 475 and the 180° rotation of shaft 166 will advance the gear 471 six teeth during each cycle of operation of the machine. By this means, either a five or a six selection may be effected.

Four and seven selection adjustment

Also, keyed to the sleeve 179 is gear 477 (Fig. 4) and mounted for oscillation on a spacer carried by said sleeve adjacent this gear is a selection plate 478, on which are mounted idler gears 479 and 480 which are entrained with gear 477. Keyed to shaft 166 in alignment with idler 479 is a fourteen-tooth gear 481, and keyed to shaft 167 in alignment with idler 479 is a sixteen-tooth gear 482. Thus, when the selection plate 478 is swung to the right (as viewed in Fig. 4) its idler 479 will mesh with the gear 482 and the 90° rotation of shaft 167 in each cycle will serve to advance the gear 477 four teeth; while, when the said plate 478 is swung toward the left, idler 479 will mesh with gear 481 and the 180° rotation of shaft 166 in each cycle will serve to advance the gear 477 seven teeth. By this means, either a seven or a four selection may be effected.

Three and eight selection adjustment

Also, keyed upon sleeve 179 (Fig. 5) is a gear 483, and mounted to oscillate freely upon a spacer carried by the sleeve 179 adjacent this gear is a selection plate 484, similar to those above described and carrying idlers 485 and 486. Keyed to shaft 166 in alignment with idler 485 is a sixteen-tooth gear 487, and keyed to shaft 167 in alignment with idler 485 is a twelve-tooth gear 488. Thus, when plate 484 is swung to the left (as viewed in Fig. 5) its idler 485 will mesh with gear 487 and the 180° rotation of shaft 166 in each cycle will serve to advance the gear 483 eight teeth; while when plate 484 is swung toward the right, idler 483 will mesh with gear 488 and the 90° rotation of shaft 167 in each cycle of operation will serve to advance the gear 483 three teeth. By this means, either an eight or a three selection may be effected.

Two and nine selection adjustment

Also, keyed to the sleeve 179 is a broad faced gear 189 (Fig. 6), and freely mounted for oscilla-

tion on a spacer carried by the sleeve 179 on one side of this gear is a selection plate 490, similar to those above described, and mounting idlers 290 and 291. Keyed to shaft 166 in alignment with idler 291 is an eighteen-tooth gear 493, and keyed to shaft 168 is a twenty-four tooth gear 495 which meshes with a gear 494 rotatably mounted upon shaft 167 in alignment with idler 291. Thus, if plate 490 is swung to the left (as viewed in Fig. 6) idler 291 will mesh with gear 493 and the 180° rotation of the shaft 166 in each cycle will serve to advance the gear 189 nine teeth; while, if the plate 490 is swung toward the right, the idler 291 will mesh with the gear 494 and the 30° rotation of shaft 168 in each cycle will drive gear 494 through gear 495 to advance the gear 189 two teeth. By this means, either a nine or a two selection may be effected.

One selection adjustment

Mounted for oscillation on sleeve 179 at the opposite side of gear 189 is another selection plate 496 (Fig. 7) having mounted thereon intermeshing idler gears 497 and 498. Gear 498 is constantly enmeshed with gear 189, while gear 497 may mesh with the twenty-four tooth idler gear 499, which is rotatably mounted on shaft 167 when the plate 496 is swung to the right (as viewed in Fig. 7). This gear 499 is driven by a twelve-tooth gear 200 keyed on shaft 168 so that gear 189 will be advanced a single tooth upon a 30° rotation of gear 200 when plate 496 is swung to the right.

Zero selection adjustment

A zero selection is effected by holding gear 189 against rotation. For this purpose, a pawl 201 (Fig. 7) is mounted upon a shaft 202, so that when the plate 496 is swung to the left the edge of said plate will engage an ear 203 on pawl 201 and retain said pawl in engagement with the gear 189 after the shaft 202 is rocked, as herein-after described.

The shaft 202 extends across all orders of the machine and one pawl 201 is provided for each decimal order. At the commencement of operation, shaft 202 is rocked counter-clockwise to a limited extent by a mechanism to be presently described, and when the machine comes to rest the shaft is returned in a clockwise direction. It will be noted that pawl 201 is provided with narrow keys 204 lying in wider key-ways in the shaft 202 and, therefore, when some value other than zero is selected in a given order the initial counter-clockwise rocking of shaft 202 will free pawl 201 so that upon rotation of sleeve 179 the gear 189 may rock its associated pawl 201 out of the way. However, if a zero is selected in a particular order, the associated plate engaging the lug 203 of the pawl 201, as previously explained, will retain the pawl in engagement with the gear 189, notwithstanding the counter-clockwise movement of the shaft 202, because the key-way in which the keys 204 are engaged is wide enough to permit such limited rocking movement of the shaft 202 as is necessary in this operation. By this arrangement, when the selection plate 496 is swung toward the left, as viewed in Figure 8, the gear 189 is locked and the zero selection is effected.

It will be apparent from the foregoing that one of the five selection plates in each order is positioned during a selection operation to select either a numeral value or zero while the remaining four plates of that order are held in idle

position. The value positions are positions in which the plate-carried gears mesh with gears on shafts 166 or 167, while the idle position is the intermediate position of the plates in which no such connection is effected. Thus, if a six is to be selected, by way of example, plate 472 (Fig. 3) will be swung to the left to engage gear 475, while all the other plates will be held in intermediate positions.

Selection locking provision

Means are provided to lock the plurality of selection plates 472, 478, 484, 490, and 496 (Figs. 3, 4, 5, 6, and 7) in one of their three positions during the actuation period. A shaft 115 (Fig. 3) is rocked counter-clockwise just before the actuation period by mechanisms explained hereinafter. A lever 183 is secured to this shaft and is connected to a lever 184 pivoted on a shaft 188. A selection locking bail 185 is secured to lever 184 and extends across the machine so that a flange 186 thereon may be moved upwardly into one of the three notches 187 to lock all the selection plates in one of the three positions described hereinbefore. After the actuation cycles are completed, the shaft 115 is rocked back to the position shown, which rocking moves the flange 186 out of the notches 187 so that the plates may be moved to a new setting indicative of the next selection entered on the keys 15 (Fig. 1.)

Driving mechanism

The operating cycle of the present machine is divided into three phases; a setting phase, an actuating phase, and a restore and shift phase of approximately twelve and one-half per cent, seventy-five per cent, and twelve and one-half per cent of the cycle, respectively.

Means are provided to enmesh the carriage 40 drive gear 271 (Fig. 1) with the actuator pivot gear 189 during the setting phase, and to accomplish this a direct drive is established from the crank handle 100 (Figs. 1 and 10) to a dipping cam 108. Crank 100 is made integral with gear 103 and shaft 102. Gears 103, 104, 105, and 106 are constantly in mesh, and since gears 103 and 106 have the same number of teeth one turn of the crank 100 effects one complete rotation of gear 106 and of shaft 107 and cam 108 integral therewith.

On a stud 109 (Fig. 1) is freely pivoted a bell crank 110 provided with a roller 111 which lies in the plane of cam 108. A second roller 113 is provided on said bell crank which cooperates with a downwardly extending arm 114 to effect a rocking of shaft 115 to which arm 114 is secured. Also, integrally secured to shaft 115 are two dipping arms 116, on each of which are mounted two rollers 117 adapted to embrace the dipping bail 269. As described in the Avery Patent No. 2,271,240, this bail 269 is disposed laterally in the machine and is secured to the rear end of each of the carriage brace plates 266, so that when the bail 269 is lowered all gears 271 move into mesh with the actuator pivot gears 189. The cam 108 is so designed that it completes its rise in the first 45° of its rotation in either direction from the position shown in Figure 1, so that the carriage will be dipped and ready for actuation when the hand-crank cycle is twelve and one-half per cent complete.

Accumulator

The actuation of the numeral wheels 279 is effected by mechanism, including the above-mentioned pivot gears 189 (Fig. 1) which mesh with

the gears 271 mounted in the shiftable carriage. Gears 273 meshing with the gears 271 are integral with two plates 292 and 296 (Fig. 8) between which are journaled the planetary gears 298. These planetary gears revolve about a sun gear 299 and drive the ring gear 276 and its integral numeral wheel 279 in a manner more completely described in the Avery Patent No. 2,222,164, dated November 19, 1940, to which reference may be had for a full description of portions of the accumulator mechanism not specifically disclosed herein.

In addition to this direct actuation of the numeral wheels by the actuator unit, a tens carry mechanism is provided whereby one complete revolution of a numeral wheel will effect one-tenth of a revolution of the numeral wheel immediately to the left. This is accomplished through a direct ten to one planetary gear train from one numeral wheel to the next, which train consists of gear 280 (Fig. 8) integral with the numeral wheel 279, planetary gears 309 and 308, ring gear 301 integral with the sun gear 299, and planetary gears 298 which drive the ring gear 276 integral with the next higher numeral wheel.

Numeral wheel aligning mechanism

Obviously, if the numeral wheel to the right in Figure 8, for example, is driven one-half a revolution or five digital increments, the numeral wheel to the left will be driven one-half of one-tenth of a revolution or half the distance between numerals. After the actuation is completed, it is necessary to back up the left-hand numeral wheel by the amount of this partial increment so that the numeral can be read through the dial opening in the carriage cover. For this purpose, a numeral wheel aligning cam 281 (Figs. 1 and 8) is made integral with the numeral wheel and is so shaped as to permit the cam follower 315 to be rocked upwardly from the position shown in Figure 1, by an amount proportional to the digit displayed on the numeral wheel. An ear 314 (Figs. 1 and 9) of a rocking segment 313 underlies the cam follower 315 so as to limit the clockwise movement of said rocking segment in accordance with the current position of the cam follower 315, thereby rocking the segment plate 304 which carries planetary gears 308 and 309. Therefore, these planetary gears are backed up by movement of the segment 304 through an angle which cancels the amount they are rotated by the gear 280, and, as explained more in detail in the last-mentioned Avery patent, the next higher dial is likewise backed up by the same partial increment it receives through the tens carry train.

In the present machine the numeral wheel aligning mechanism is disabled during positive operation in order to avoid the great resistance to numeral wheel rotation that would result if the cam followers 315 (Fig. 1) were to be simultaneously driven up the steep cam rises in a number of adjoining orders, as for example when a series of numeral wheels stand at nine and the lowest order of the series is driven by the actuator from nine to zero. When operating negatively in division, however, it is necessary that the operator be immediately warned when an overdraft occurs and the numeral wheel aligning mechanism is not disabled during negative operation in a manner that will appear from the following description.

When the machine is operated negatively until the numeral wheels 279 are reduced to the zero position, shown in Figure 1, the cam followers 315 are rocked the farthest distance from

the center of cams 281. If a digit is again subtracted, the numeral wheel and its integral cam 281 are rotated clockwise, which allows the roller 316 to move from the extreme high or zero point 5 of the cam to the extreme low or nine position. An ear 314 is formed on the segment 313 (Fig. 9) and underlies the cam follower 315 (Fig. 1) so that when said cam follower is released by cam 281 the spring 317 rocks the segment 313 and 10 cam follower 315 clockwise, and coincidentally rocks a second segment 304 (Fig. 9) counter-clockwise. On the segment 304 are mounted two integral planetary gears 309 and 308 (Figs. 8 and 9), and during this counter-clockwise rocking of 15 segment 304 the gear 309 revolves about the sun gear 280 and the second planetary gear 308 revolves inside the ring gear 301, thus imparting counter-clockwise rotation to spider 300 and its integral sun gear 299. 20 The planetary gears 298 mesh with both sun gear 299 and ring gear 276, which latter is integral with spider 274 and the numeral wheels 279. Therefore, the counter-clockwise rotation of sun gear 299 imparts clockwise rotation to sun gears 298 about their own centers and clockwise rotation to the next higher order numeral wheel 279 from zero to nine. Secured to this next higher order numeral wheel is also a cam 281 which is rotated to effect a repetition of the movements 25 just described, from that order to the immediate higher order, thus setting up a carry wave to all nines leftward across the carriage.

From the above explanation, it will be noted that if the numeral wheel aligning mechanism 35 were disabled until the completion of the current actuation the "carry wave" would likewise be delayed until the completion of that actuation, and since the movement of the highest order accumulator numeral wheel from zero to nine serves 40 to indicate an overdraft, this operation too would be delayed until the completion of actuation.

Mechanism has, therefore, been provided to free cam followers 315 from their cooperation with cams 281 during positive operation only, as described hereinafter.

A cam 60 (Figs. 1 and 10) is made integral with a gear 62, the unit thus formed being freely rotatable on shaft 166 and driven by a gear 118 keyed to shaft 107 (Fig. 10). The arrangement is such 50 that cam 60 is rotated through the same angles and in the same direction as crank 100. As can be seen in Figure 1, a clockwise rotation of crank 100 and gear 103 will rotate gear 104 counter-clockwise, gear 105 clockwise, gears 106 and 118 (Fig. 10) counter-clockwise, and gear 62 and cam 60 clockwise (Fig. 1).

A stud 65 (Fig. 1) is secured to a frame of the machine and on it are mounted two levers 66 and 70, lever 66 having a downwardly extending arm 69 which follows the cam 60 and is normally held in the position shown in Fig. 1 by the spring 68. On the lever 70 is formed an ear 71, which is adjacent the arm 69, and a second ear 74 which is formed laterally toward the left side of the machine and designed to operate in the plane of a lever 75. A spring 78 urges lever 70 in a clockwise direction to the limit provided by a stationary ear 84. A shaft 80 is disposed laterally in the carriage of the machine and is supported by the 65 lower carriage brace plates 266. One of the levers 70 is keyed to said shaft in each denominational order, so that no matter what position the carriage may be in the ear 74 will contact one of the levers 75 whenever it is rocked in a counter-clockwise direction. This counter-clockwise rocking of

ear 74 will cause a clockwise rocking of shaft 80, and the members 76 which are provided in each order of the register will be rocked around and by contacting ear 318 will move cam followers 315 away from the cams 281.

As stated above, cam 60 rotates in the same direction and at the same speed as the hand-crank 100. Therefore, when the hand-crank is rotated clockwise for positive actuation cam 60 will move tip 69 to the right (Fig. 1) and lever 66 in a counter-clockwise direction. Ear 71 on lever 70 will be effective to transmit this movement to ear 74, which movement is effective as previously described to rock the followers 315 away from the numeral wheel cams 281. On the other hand, if the hand-crank is rotated counter-clockwise for negative operation, cam 60 will move tip 69 to the left, which is away from the ear 71, and, therefore, ear 74 will not be moved and the followers 315 will remain in cooperation with the cams 281.

Selective ration transmission

The drive from the hand-crank to the actuator runs through a selective ratio transmission unit, which consists of a series of gears 121 to 129, inclusive (Fig. 10), freely mounted on shaft 120, and a second series of cooperative gears 131 to 139, inclusive, securely mounted on shaft 130. The gears 103 and 104 have the same number of teeth, and gear 104 is secured to shaft 120 so that this shaft will always rotate an angular amount equal to that of the crank.

Each of the gears 121 and 129 has welded thereto or otherwise made integral therewith a centralizer and interlocking disc 141 (Figs. 10 and 2). Keyways 142 are provided in the gears 121 to 129 and the discs 141. These keyways are somewhat wider than the thickness of a key 140 to facilitate shifting of the key from one gear to another. As shown in Figure 10, the shaft 120 has a deep keyway cut in one side to receive the slideable key 140. It will be noted that the key terminates at its rightward end in a driving tongue, the length of which is slightly shorter than the combined thicknesses of a gear 121 to 129 and its respective disc 141. From the foregoing, it may be seen that by sliding the key 140 along the shaft 120, as for example by means of the multiplier setting mechanism shown in said Avery application, Serial No. 367,025, one may establish a positive drive from the shaft 120 to a selected gear 121 to 129, which in turn will drive its respective gear 131 to 139 integral with shaft 130.

In Figure 1 the gear 121 is shown and it will be noted that it has several teeth removed. The removal of these teeth serves two purposes: (1) in case shaft 130 is driven through some other pair of gears it provides clearance in which gear 131 may turn; and (2) if this pair of gears serves as the driving means it allows for the twelve and one-half per cent idle period, termed the setting phase, during which the register gears 271 are moved into mesh with the actuator gear 189 before the drive begins.

Obviously, a great many arrangements could be devised to give a desired operation. For example, one may desire to have the gears all of the same diametral pitch, but this would make it necessary to vary the idle period of each set of gears. The combination, however, which seems most desirable is to maintain a constant idle period and vary the pitch. The following tabulation is one alternative where the idle period is

constant and the diametral pitches vary accordingly.

Table A

Selection	1	2	3	4	5	6	7	8	9
Diametral pitch	26	25.5	28	25	29	27.5	37	41	30
Gears	#131	#132	#133	#134	#135	#136	#137	#138	#139
Number of teeth	36	27	24	18	18	15	18	18	12
Gear	#121	#122	#123	#124	#125	#126	#127	#128	#129
Number of teeth effectively driven	12	18	24	24	30	30	42	48	36
Teeth of complete gear	16	24	32	32	40	40	56	64	48
Idle period	25%	25%	25%	25%	25%	25%	25%	25%	25%

It will be noted in the first column of the table that gear 121 is a sixteen-tooth gear with the number of teeth it will effectively drive as twelve, which is exactly seventy-five percent of sixteen; while in Figure 1, gear 121 is shown with only ten teeth. This is because the first tooth of gear 121 would contact one tooth before the one on the center line, and upon completion of the actuation the last tooth of gear 121 would wipe its respective tooth one space past center. This would cause an effective drive of two teeth more than the actual number of driving teeth. Therefore, in this case, the number of teeth remaining is two less than the desired number of teeth to be effectively driven.

If the key 140 were inadvertently positioned between two gears so as to drive them both, it would, of course, jam the transmission with both gears considerably displaced from their neutral positions. To prevent this, means are provided whereby the key 140 can never drive two gears 121 to 129 out of their neutral positions at the same time. The disc 141 (Figure 2) is provided with a recess into which is pressed the nose of pawl 143 by the tension of spring 144, which tends to maintain the pawl 143 in its extreme clockwise position shown. Underlying a shoulder 145 of the pawls 143 are a series of balls 146 (Fig. 10) which are held in a retainer 147. The length of this retainer is equal to the combined diameters of all the balls plus the thickness of one pawl 143. The balls are free to roll a limited amount sufficient to allow one pawl at a time to enter between a pair of balls. In viewing Figure 2, it will be seen that when the key 140 is positioned in the order shown, for example, the gear and disc 141 may be rotated and immediately thereupon the pawl 143 is rocked counter-clockwise about shaft 149 and passes between two of the balls as shown by the dotted lines 148 (Fig. 10). If the key 140 is midway between two positions, however, an attempt will be made to drive two gears, but this will be impossible because two pawls can not enter the retainer at the same time; the result being that neither can be rocked counter-clockwise far enough to permit the disc and gear to turn appreciably until the key is correctly aligned.

With the transmission thus controlled, the gear selected may rotate but all others will be held in their neutral positions. Since the shaft 130 (Fig. 10) and all gears 131 to 139 rotate as a unit, the gear 131 is used as a convenient means to drive the actuator through the idler 150, mounted on stud 151, and gear 152 secured to the half-turn shaft 166 of the actuator. The quarter-turn and twelfth-turn actuator shafts 167 and 168 are also shown in Figure 10, which, together with shaft 166, serve to drive the register through the actuator gearing, explained hereinbefore and in the aforementioned Avery Patent No. 2,271,240. Thus, a positive selective drive may be established

between the crank and the actuator in such a way that one turn of the crank will effect from one to nine half-turns of the half-turn shaft 166 to effect the operation of the actuator through cycles of operation, depending on which gear 121 to 129 is selected to drive.

Means are provided to centralize the actuator so that gears 131 to 139 will always come to rest in a centralized position and to lock the actuator against rotation when the gears 271 (Fig. 1) are not lowered into mesh with the actuator gears 189, and further to lock the gears 271 in their lowered position while the actuator is out of a centralized position. On the left end of the half-turn actuator shaft 166 (Fig. 12) is secured an actuator centralizing disc 153 with two oppositely disposed recesses 154, into which are urged two rollers 155 mounted on levers 156 and 157. These levers are pivotally mounted on stud 153 and constantly urged toward the disc 153 by the spring 159 tensioned between the two levers. In this manner, the pressure of the rollers 155 against the recesses 154 will hold the actuator in a centralized position, unless positively driven.

The lever 157 is provided with a slightly curved surface 160 in the form of an arc of a circle drawn around shaft 115 as a center, and on said shaft is secured an arm 171, on opposite sides of which are mounted two rollers 172 and 178 (Fig. 11). Of these, roller 178 is adapted to sweep across the arcuate surface 160 and prevent clockwise movement of lever 157. The parts in Figure 12 are shown in the position they assume when the gears 271 (Fig. 11) and related parts, frequently called "the lower carriage," are in a raised position. When, however, the lower carriage is dipped, as previously described, the levers 116 and 171 rock counter-clockwise with shaft 115 until the roller 178 (Figs. 11 and 12) assumes the position 178-A. In this position lever 157 is free to be forced rearwardly by disc 155 when the actuator turns.

When the lever 157 is forced rearwardly in this manner the shoulder 151-A lies in the return path of roller 178 and thus locks the lever 171 and the lower carriage against return movement until the actuator approaches a centralized position, when the rollers 155 again become seated in the recesses of disc 153.

Means are provided to lock the gears 189 (Fig. 11) in correct alignment after the actuating phase is completed so the carriage may be subsequently lowered into mesh with the actuator without the gears 189 and 271 clashing. The second roller 172 on lever 171 sweeps across the arcuate surface 174 of lever 175 (Fig. 11) to lock said lever against clockwise movement about stud 158 in the same manner that roller 178 locked the lever 157. A lever 586 is keyed to shaft 202 and is provided with a bifurcated lower end which embraces stud 176 of lever 175. Also, on shaft 202 are loosely keyed a series of ordinal pawls 201 which engage between the teeth of each pivot gear 189. On viewing Figure 11, it will be seen that pawl 201 is forced against gear 189 so that when the lower carriage is dipped for actuation the teeth of gear 189 will be in a position to receive the gear 271. When the roller 172 is moved downwardly, lever 175 is free to be rocked clockwise by spring 177 to rock lever 586 and shaft 202 counter-clockwise, so that if a selection is made in the order shown in Figure 11 the gear 189 may turn on shaft 170 and force the pawl 201 clear of the teeth. The

way in which ear 203 serves to hold the pawls 201 in all unset orders, so the unactuated gears 189 can not float out of alignment, was explained briefly hereinbefore and may be found in more detail in the aforesaid Avery Patent No. 2,271,240.

From the foregoing description then, it may be seen that by making a "nine" selection on the selective transmission, shown in Figure 10, and by depressing a "nine" key 15 (Fig. 1), a single turn of the hand-crank rotates the numeral wheel aligned with the key depressed eight and one-tenth revolutions. During this plural cycle operation of the actuator the cam 108 makes only one revolution and, therefore, holds the carriage gears 271 in mesh with the actuator gears 189 during the entire operation. Similarly, the cam 60 makes only one revolution irrespective of the values selected and holds the numeral wheel aligning cam followers 315 away from the cams 281 so that they may make any number of revolutions in a counter-clockwise or plus direction without subjecting the cam and related mechanism to the strain resulting from the cam rocking the cam follower over the steep rise thereof. Likewise, the bail 185 (Figs. 3, 4, 5) locks the selection plates 472, 478, 484, etc., the pawl 201 (Fig. 11) unlocks the actuator gears, and the arm 171 (Fig. 12) unlocks the actuator centralizer disc 153 for this plural cycle operation irrespective of the number selected.

I claim:

1. In a calculating machine having in combination with a register, a cyclically operable actuator therefor, means for normally locking said actuator in centralized position, a cyclically operable driving member, and a drive train between said driving member and said actuator, a selective ratio transmission in said train for driving said actuator a plurality of cycles in response to a single cycle of operation of said driving member, a cam operable through a single cycle in response to a single cycle of operation of said driving member, and control means operable by said cam in response to a single cycle of operation thereof to render said actuator locking means ineffective throughout said plurality of cycles of said actuator.

2. In a calculating machine having a register, an actuator therefor, selection mechanism set-table in accordance with selected numeral values for controlling said actuator, a cyclically operable driving member, and a drive train between said driving member and said actuator, a selective ratio transmission in said train for driving said actuator a plurality of cycles in response to a single cycle of operation of said driving member, a cam operable through a single cycle in response to a single cycle of operation of said driving member, and means operable by said cam in response to a single cycle of operation thereof in one direction to lock said selection mechanism in set position throughout said plurality of cycles of said actuator.

3. In a calculating machine, a register, a cyclically operable actuator therefor, a cyclically operable driving member, a drive train between said driving member and said actuator including a selective ratio transmission operable to drive the actuator a selected number of cycles in response to a single cycle of operation of said driving member, a cam driven by said driving member through a single cycle of operation in response to a single cycle of operation of said member, and control

means operable by said cam in response to a single cycle of operation thereof in one direction to enmesh said register and said actuator prior to operation of said actuator, to maintain said register and actuator in mesh throughout said selected number of cycles of the actuator and to demesh said register and actuator subsequent to said operation of the actuator.

4. In a calculating machine having a register, numeral wheels thereon, numeral wheel aligning means comprising a cam mounted for rotation with each of said numeral wheels, and a cam follower to cooperate with each of said cams, a reversible cyclically operable actuator for said numeral wheels, a reversible cyclically operable driving member, a selective ratio transmission deriving power from said driving member during one cycle of operation thereof for driving said actuator through a plurality of cycles in either direction, a control element driven by said driving member through a single cycle of operation in either of two directions in response to a single cycle of operation of the driving member in either respective direction, and control means operable by said control element in response to a single cycle of operation thereof in one of said two directions to rock and hold said cam followers beyond the periphery of said cam throughout said plurality of cycles of the actuator.

5. In a calculating machine, the combination of a register, an actuator therefor, a cyclically operable driving member, a drive train between said member and said actuator including a selective ratio transmission, and means for selectively setting said transmission to enable the same to drive said actuator through a selectively variable number of cycles of operation in response to a single cycle of operation of said driving member; with means for conditioning said actuator for operation prior to the selective cyclic

operation thereof and for normalizing the same at the completion of said cyclic operation, a cam driven through a single cycle in synchronism with said driving member upon operation of the latter through said single cycle, and means controlled by said cam in response to said single cycle of operation thereof to operate said conditioning means as aforesaid prior to and subsequent to operation of the actuator through said variable number of cycles.

6. In a calculating machine, the combination of, a register, a cyclically operable actuator therefor, a selective ratio transmission comprising, a cyclically operable driving unit each cycle thereof having an initial idle phase, a driving phase and a second idle phase, and a driven unit operable through a selectively variable number of cycles in response to a single cycle of operation of said driving unit; with means for selectively setting said transmission to enable the same to drive said actuator through a selectively variable number of cycles corresponding to the number of cycles of said driven unit, a device operable to condition said actuator for operation and to restore the same to normal condition, a cyclically operable cam having a conditioning phase and a restore phase of each cycle, said cam being effective upon operation thereof through said conditioning phase to cause said device to condition said actuator during the initial idle phase of said driving unit and effective upon operation thereof through said restore phase to cause said device to restore said actuator during the second idle phase of said driving unit, a cyclically operable driving member, and means connecting said member to said driving unit of said transmission and to said cam for driving said unit and said cam in synchronism with said member.

HOWARD M. DUSTIN.
